(57) **CLAIM**

The ornamental design for pliers, as shown and described.

DESCRIPTION

The patent or application file contains a least one drawing executed in color. Copies of this patent or patent application publication with color drawing(s) will be provided by the Office upon request and payment of the necessary fee.

FIG. 1 is a top, front and right side perspective view of pliers, showing a first embodiment of my new design,

FIG. 2 is a right side view thereof;

FIG. 3 is a left side view thereof;

FIG. 4 is a bottom view thereof;

FIG. 5 is a top view thereof;

FIG. 6 is a front view thereof;

FIG. 7 is a rear view thereof;

FIG. 8 is a top, right side and rear perspective view of pliers, showing a second embodiment of my new design;

FIG. 9 is a right side view thereof;

FIG. 10 is a left side view thereof;

FIG. 11 is a bottom view thereof;

FIG. 12 is a top view thereof;

FIG. 13 is a front view thereof; and,

FIG. 14 is a rear view thereof.

The features shown in broken lines show portions of the pliers that form no part of the claimed design.

1 Claim, 12 Drawing Sheets
